UNITED STATES PATENT OFFICE.

EDWARD C. WOODARD, OF BROCKTON, MASSACHUSETTS.

ADJUSTABLE HANDLE FOR BICYCLES.

SPECIFICATION forming part of Letters Patent No. 527,576, dated October 16, 1894.

Application filed July 12, 1894. Serial No. 517,293. (No model.)

To all whom it may concern:

Be it known that I, EDWARD C. WOODARD, of Brockton, in the county of Plymouth and State of Massachusetts, have invented certain new and useful Improvements in Adjustable Handles for Bicycles, of which the following is a specification.

The object of the present invention is to provide an improved construction of adjustable handle-bars for bicycles, so arranged that the rider can readily change the adjustment without stopping to dismount, and moreover permitting the handle-bars to be folded when desired to compact the bicycle for shipment, or to accommodate it to limited space.

An embodiment of the invention is illustrated in the accompanying drawings which form part of this specification, and of which—

Figure 1 shows an elevation of the parts embodying the invention, as viewed from the rear, with a portion of the steering head appearing, and part of the frame in section, the handle-bars being represented as spread to the limit. Fig. 2 shows a top plan view of the same parts. Fig. 3 shows a side elevation, with the handle-bars folded. Fig. 4 shows a front view, with the handle-bars folded.

In the drawings—the letter *a* designates the steering head, which receives the stem of the front fork in a bicycle of the well-known safety type, and *b* designates the handle-bar post, which is of tubular form and fits within the steering head. Said post has at its upper end a rigid cross-head *b'*, which is bifurcated vertically at its ends to receive ears on the handle-bars *c*; and pivots *c'* are passed through the bifurcations and ears, so as to permit movement of the handle-bars up and down. Movement of the handle-bars on these pivots not only secures vertical adjustment, but also provides for swinging the handle-bars downwardly to inoperative positions beside the frame of the machine, as shown in Figs. 3 and 4, this being of great advantage in shipping and also when leaving the bicycle standing, for it not only reduces the space occupied, but also prevents use of the machine and is thus a protection against theft.

In order to maintain the two handle-bars always in corresponding positions, the following equalizing connections are employed: A rod *d* is fitted to slide vertically in the post *b*,

and carries a cross-head *d'* at its upper end. Curved equalizing links *e* connect said cross-head with the handle-bars respectively, said links being jointed at their upper ends to the cross-head, whose ends are bifurcated to receive them, and jointed at their lower ends to bifurcated lugs *e'* on the handle-bars. It will now be seen that the connections above described will cause a corresponding movement of either handle-bar when the other is moved, the rod *d* sliding in the post. This post also constitutes a convenient part for application of locking devices. A set-screw *f* is entered through an internally screw-threaded boss *f'* on the rear side of the post, so as to bear against the rod *d*, and this screw has a handle *f''* by which to turn it and lock or unlock the handle-bars. The screw *f* affords a convenient and easily manipulated means by which the rider can set the handle-bars without dismounting.

I provide an additional device for locking the handle when the bicycle is to be left standing. This device is in the form of a set-screw *g* entered through a suitably formed boss on the front side of the post and arranged to bear against the rod *d*. This set-screw is made with a triangular head or outer end *g'* requiring a wrench of special construction to turn it, and the special function of this screw is to lock the handles in their operative adjustment, and prevent use of the machine. The peculiar form of the screw's head prevents it from being turned by an ordinary implement.

It will now be seen that my invention provides for the depression of the handle-bars to an inoperative position, and for their upward movement from said position to variously elevated operative positions, the equalizing connections being movable of the handle-bars to a sufficient extent to permit the handle-bars to occupy the various positions mentioned, said positions extending through a wide range of adjustment. It will also be seen that the set-screw, *f*, co-operates with the equalizing connection in positively securing the handle-bars in either of the operative positions to which they may be adjusted, so that the rider may, without dismounting, change the height of the handles and secure them at any height desired.

The invention also provides for reducing the compass of the bicycle to accommodate it to limited space, and for effectually locking the handle-bars in their inoperative adjustment.

It is evident that the equalizing means shown may be modified without departing from the invention.

What I claim as my invention is as follows:

- 10 1. In a bicycle, the combination of the handle-bar post, handle-bars pivotally connected to said post and each adapted to swing downwardly to an inoperative position beside the frame of the machine, and to be adjusted upwardly from said position to variously elevated operative positions, movable equalizing connections between said handle-bars, whereby said bars are caused to maintain corresponding positions, and a fastening device co-operating with said connections whereby the handle-bars may be positively secured in any operative position to which they may be adjusted.
- 15 2. In a bicycle, the combination of a hollow handle-bar post, handle-bars pivoted thereto so as to move in a vertical plane, a slide fitted to the post, and equalizing links connecting said slide with the handle-bars.
- 20 3. In a bicycle, the combination of a hollow handle-bar post, handle-bars pivoted thereto to move in a vertical plane, a rod fitted to

slide in the post, equalizing links connecting said rod and the handle-bars, and a set-screw in the post arranged to bear against the rod.

4. In a bicycle, the combination of a hollow handle-bar post, handle-bars pivoted thereto to move in a vertical plane, a rod fitted to slide in the post, equalizing links connecting said rod and the handle-bars, and a set-screw in the post arranged to bear against the rod, and having a triangular head.

5. In a bicycle, the combination of a handle-bar post, handle-bars pivoted to move in a vertical plane, equalizing connections between the bars, and a lock for fixing the bars to the post in their folded adjustment.

6. In a bicycle, the combination of a hollow handle-bar post, handle-bars pivoted thereto to move in a vertical plane, a rod fitted to slide in the post, equalizing links connecting said rod and the handle-bars, and a lock for fastening the sliding rod and the post together.

In testimony whereof I have signed my name to this specification, in the presence of two subscribing witnesses, this 9th day of July, A. D. 1891.

EDWARD C. WOODARD.
